UNITED STATES PATENT OFFICE.

ROBERT F. HALLEN, OF NEW YORK, N. Y.

GLUING-MACHINE.

1,175,257.

Specification of Letters Patent. Patented Mar. 14, 1916.

Application filed May 4, 1914. Serial No. 836,134.

To all whom it may concern:

Be it known that I, ROBERT F. HALLEN, a citizen of the United States, residing in New York, county of Bronx, and State of New York, have invented a certain new and useful Improvement in Gluing-Machines, of which the following is a specification.

My invention relates to machines for applying adhesive material, as glue or paste, to cards or similar articles, particularly to those cards to which a piece of cloth is pasted for display purposes; and it has for its object to do this work in a more neat, expeditious and positive a manner than it can now 10 be done by dipping a brush in the paste contained in a cup and spreading said glue on the card. My invention avoids this slow, tedious and uneven process and accomplishes in one hour what it now takes more than 15 two hours to do. I gain this object and result by means of the device presently described and shown in the accompanying drawings forming part of this application, and in which,—

Figure 1, is a front elevation of my machine. Fig. 2, a side view with one of the end pieces removed disclosing one of the levers that supports and operates the pad-carrier, as well as the mechanism that operates the roller through the upward movement of said lever; and Fig. 3, is a view of the said end-piece. Fig. 4, being a cross-section of the front leg of said end-piece on the line A—A, showing the form thereof at 25 this point; while Fig. 5, is a cross-section of said front leg on the line B—B, showing its form at this point.

Similar numerals of reference designate corresponding parts throughout the several 30 views.

My invention consists of two castings or supports 1 and 2, preferably of the triangular form shown, secured in an upright position to a foundation X, and connected by 35 sustaining rods or other suitable means. The front edge of the front legs of these supports are straight to the point X' and are of the form shown in cross-section in Fig. 4; from which point they convex inwardly to 40 X²; at which point the face divides and assumes the form shown in cross-section in Fig. 5, the lower track continuing its inward curve to X³, while the upper track continues concavely to X⁴. These faces form 45 guides or tracks for the ends of the pad-carrier 3, and while the formation need not be

as shown, yet this is preferable in order to permit the gluing-pad to contact with both the roller and cards in the most efficient manner; the pad-carrier 3 being provided at each end with two fingers 3' and 3² (preferably provided with rollers). After traveling up the straight face of the supports to X', the lower fingers take the lower track to X³, and the upper fingers take the upper track to X⁴, the formation throwing the lower part of the carrier inwardly and bringing the whole surface of the pad in contact with the roller whereby the entire face of said pad receives a supply of paste; and upon the downward movement of the carrier, the straight face of the supports throw the lower part of the carrier outward, thereby causing the said carrier to present the whole face of the pad to the card to be 50 mounted. Instead of the front edge of the legs of the support being used for the tracks, the inside faces of said legs can be grooved and the fingers of the carrier move in said grooves without departing from the spirit 55 of my invention. This pad-carrier 3 is sustained and its ends kept in close contact with the tracks at all points thereof by means of two levers, one at each end of the machine; these levers consisting of a rod 4, one 60 end of which is attached to the carrier 3 at 4', and the other end supported in a housing 5, the opposite end of which housing is secured to a shaft at the rear of the machine journaled in bearings 5'. The rod 4 is adapted 65 to slide in the housing 5 and operates to hold the pad-carrier 3 in contact with the tracks by means of a spiral-spring 6 inclosed in said housing and surrounding the rod, with one end secured to the same at 6' 70 and its other end bearing against the end of the housing at 6². To the under side of this carrier 3 is secured a gluing pad 7 so arranged that it can be easily attached to or detached from said carrier by means of 75 screws 7'; and also so that its pressure can be regulated through the medium of screws 7², whereby the said pad can be made to bear against the roller in such a way as not to receive from it too heavy a supply of paste. 80 This pad is preferably made of hard rubber and corrugated as shown, the raised portions only taking the glue and applying it to the card to be pasted.

Intermediate of the supports 1 and 2 is 85 placed a pedestal or support 8 of suitable height, upon which is preferably removably

secured a glue-box 9 so arranged that it can be adjusted backward and forward by means of screws 9', or other suitable equivalents. Upon or within this glue-box 9 is preferably 5 removably mounted a roller 10 of suitable material, preferably brass; the function of which roller is to feed the glue or paste in said box to the gluing-pad 7, the said roller revolving within said box, making a partial 10 revolution each time the carrier 3 moves up through the medium of the following mechanism. The trunnion of the roller 10 extends beyond the glue-box 9 and to it is secured a gear wheel 11 intermeshing with 15 another like wheel 12 properly supported adjacent thereto. A lever 13 is pivoted so that a pawl 15 which it carries will engage the wheel 12 as the free end of said lever swings upward, revolving said wheel, which 20 in turn revolves the wheel 11 and roller 10. The lever is swung by means of a rod 14 which is secured to its under free end and the rod to the lever 4-5, the up and down movement of which imparts motion to the 25 mechanism. Upon the descent of the carrier 3 and lever 4-5, the pawl 15 does not engage the wheel 12 but slides over it, allowing the roller 10 to remain at rest. The roller, therefore, is revolved only when the 30 pad is moving to contact with it to receive a fresh spread of paste. It must be borne in mind, however, that I do not confine myself to this particular mechanism for turning the roller 10, nor to turning it in but one 35 direction, but any other construction, such as friction wheels instead of gear-wheels, or one instead of two wheels as shown, will be within the spirit of my invention.

For the purpose of regulating the application 40 of the paste to the roller, I preferably secure to the edge of the glue box and adjacent the roller 10, a scraper 16 which is adjustable to and from said roller by suitable means.

45 The machine is operated either with the foot working upon a treadle, or by motor or other power, attached to a rod 17 secured to shaft 18 passing from one lever 4-5 to the other, operating the carrier 3, whereby 50 the said rod 17, being moved up and down, transmits a like movement to said levers and carrier and brings the gluing pad alternately into contact with the roller and the card to be pasted. These cards are placed in a pile 55 on the foundation between the side guide 19 and rear guide 20, both of which are adjustably secured to said foundation. And within easy reach is a pile of the cloth that is to be pasted to the cards. The operator applies 60 the power, the levers 4-5 and carrier 3 ascend and the face of the pad 7 is brought into contact with the roller 10 as shown in dotted lines in Figs. 1 and 2, thereby receiving from said roller a supply of paste. The 65 levers and carrier immediately descend and

bring the face of said pad into contact with the top card, applying the paste thereto, as shown in full lines in said figures; the levers and carrier instantly ascending, take the pad back to the roller for a fresh supply of paste, 70 the said roller during this upward movement of the carrier, making one turn in the adhesive material, has such fresh supply thereof ready for the pad. At the same time the operator attaches the piece of cloth to 75 the pasted card and removes such mounted card from the pile, exposing the card below to the operation of the pad which is now descending.

Having now described my invention, what 80 I claim as new and desire to secure by Letters Patent is:—

1. A gluing machine consisting of a frame, a receptacle supported therein; a roller turning in said receptacle, and a pad 85 sliding in said frame adapted to contact with said roller, and means for moving said pad and roller.

2. A gluing machine consisting of a frame the front of which is curved at its top; a 90 bar suitably supported in contact with said front and adapted to move up and down the same; a pad carried by said bar; a receptacle supported within said frame; a roller turning within said receptacle adapted to 95 be contacted by said pad, and means for moving said bar.

3. A gluing machine consisting of end-pieces properly supported, the front legs of 100 which are curved at their tops; a bar suitably supported in contact with said front legs and adapted to slide up and down the same; a pad carried by said bar; a receptacle supported within said frame; a roller turning within said receptacle adapted to be 105 contacted by said pad as it is carried to it by said bar, and means for moving said bar.

4. A gluing machine consisting of end-pieces properly supported, the front legs of 110 which are curved at their tops; a bar suitably supported in contact with said front legs and adapted to slide up and down the same; a pad carried by said bar; a receptacle supported within said frame; a roller 115 turning in said receptacle adapted to be contacted by said pad, and means for revolving said roller as the bar ascends.

5. A gluing machine consisting of end-pieces properly supported, the front legs of 120 which are curved at their tops; a shaft journaled in said end pieces; levers carried by said shaft; a bar supported by said levers against the front legs of said end-pieces and so that it will move up and down 125 the same; a pad carried by said bar; a receptacle supported between said end-pieces; and a roller turning within said receptacle adapted to be contacted by said pad.

6. A gluing machine consisting of end- 130

pieces properly supported, the front legs of which are curved at their tops; a shaft journaled in said end pieces; levers carried by said shaft adapted to support a bar and 5 keep it in contact with the front legs of said end-pieces as it moves up and down the same; the said bar; a pad carried by said bar, a receptacle supported between said end-pieces; a roller turning in said receptacle adapted to be contacted by said pad; one or more wheels mounted adjacent said roller arranged to revolve the same; a lever 10 carrying a pawl adapted to engage either of said wheels and turn it; and means for 15 actuating said lever.

7. A gluing machine consisting of end-pieces properly supported, the front legs of which are curved at their tops, each provided on said curve with double guides leading in different directions; a shaft journaled in said end-pieces; levers carried by said 20

shaft; a bar supported and retained by said levers in constant contact with said front legs as said bar moves up and down them; the said bar provided at each end with 25 double projections adapted to move respectively in the guides of the curves aforesaid; a pad carried by said bar; a receptacle supported between said end-pieces; a roller turning in said receptacle adapted to be 30 contacted by said pad; one or more wheels mounted adjacent said roller arranged to revolve the same; a lever carrying a pawl adapted to engage either of said wheels and turn it; said lever being actuated by the up 35 and down movements of the levers carrying the bar, substantially as shown and described.
